[57] ABSTRACT

A flexible radiant heater assembly for radiantly heating a structure having a curved surface comprises a plurality of longitudinally flexible ribbon heaters juxtaposed in spaced parallel relationship. An upright piece extending upwardly at right angles to the plane of the ribbon heater is provided at each end of each heater. The heaters are electrically connected together in series by conductor wires joining the upright pieces of adjacent heaters. A plurality of heat-proofing and insulating holder members extend transversely of said heaters at spaced points in the longitudinal direction thereof with each of the holder members being secured to a major face of each of the heaters. The major surface of each heater has an adiabatic fabric mounted thereon and the holder members hold the heater and fabric together by compression. The outermost ones of the holder members are secured to the upright pieces at the ends of the heaters. Legs secured at the opposite ends of each of the holder members depend vertically therefrom and extend beyond the other major surface of each of the heaters so as to hold the heaters in spaced relationship from the surface to be heated.

ELECTRIC HEATER ASSEMBLY

BACKGROUND OF THE INVENTION

This invention relates to a radiant electric heater assembly suitably employed for radiantly heating a structure having a curved surface such as a ship hull, tubular body or the like.

Large structures having curved surfaces employed in various industrial fields are required to be heated. For example, in the ship building industry, welded joints on ship hulls are required to be heat-treated. According to one of the conventional methods for heat-treating structures having curved surfaces, a structure having a curved surface to be heated has been heated by winding an insulated nichrome wire about the structure. Alternatively, according to another conventional method, such a structure has been heated in an induction heating apparatus. However, both of the conventional heating methods require relatively cumbersome preparation operating and are low in operative efficiency. In addition, the induction heating requires an undesirably large scale facility and the design of such a facility has to be varied depending upon the size and shape of a structure to be heated.

SUMMARY OF THE INVENTION

Therefore, one object of the present invention is to provide a radiant electric heater assembly and apparatus which facilitates preparation for heating operation for a structure having a curved surface.

Another object of the present invention is to provide a heater assembly and apparatus of the above type which can be versatilely applied to structures having varying sizes and curvatures to be heated.

According to the present invention, there has been provided an electric heater assembly for radiantly heating a structure having a curved surface comprising a plurality of longitudinally flexible ribbon heaters juxtaposed in parallel and spaced relationship; means for electrically connecting said heaters; an electric power supply for supplying electric power to said heaters; heat-proofing and insulating holder members extending transversely of said heaters at spaced points in the longitudinal direction of each of the heaters on one major surface of each of the heaters, each of said holder members being secured to one major surface of each of the heaters; legs secured to said holder members depending vertically therefrom and extending beyond the other major surface of each of the heaters for holding the heaters in spaced relationship from the surface of the structure to be heated.

The above and other objects and attendant advantages of the present invention will be more readily apparent to those skilled in the art from a reading of the following detailed description of the invention in conjunction with the accompanying drawing in which one preferred embodiment of the invention is shown for illustration purpose only, but not for limiting the scope of the same in any way.

BRIEF DESCRIPTION OF THE DRAWING

FIG. 1 is a perspective view of one preferred embodiment of radiant electric heater assembly constructed in accordance with the present invention with portions thereof broken away;

FIG. 2 is a cross-sectional view taken substantially along the line 2 — 2 of FIG. 1 and showing one heater and its associated parts of the assembly;

FIG. 3 is a cross-sectional view taken substantially along the line 3 — 3 of FIG. 1 and showing another portion of the heater and its associated parts of FIG. 2;

FIG. 4 is a view of an arrangement of a plurality of heater assemblies each corresponding to that as shown in FIG. 1 which arrangement is for heating a structure having a large curved surface; and

FIG. 5 is a view showing mechanical and electrical connections between adjacent heater assemblies in said arrangement of FIG. 4.

PREFERRED EMBODIMENT OF THE INVENTION

The present invention will be now described referring to the accompanying drawing and more particularly, to FIG. 1 thereof. In FIG. 1, one preferred embodiment of the heater assembly of the invention is generally shown by reference numeral 1 and the heater assembly generally comprises a plurality of longitudinally flexible ribbon heaters 2 which are juxtaposed in such a spaced relationship that the axes of these heaters extend parallel to each other. Each of these heaters 2 comprises a conventional electric heating strip which is essentially flexural or flexible in the longitudinal direction and therefore, the strip is required to have a relatively small thickness such as 1 mm, for example. The heater or strip 2 has at the opposite ends integral upright pieces 2a formed by upwardly bending the strip 2 at the opposite ends at right angles to one of the major surfaces of the strip 2. The adjacent ribbon heaters 2 are electrically connected at alternate one end upright piece 2a of each heater by means of a conductor wire 3. The other end upright pieces 2a of the outermost ribbon heaters 2 are provided with conductor wires 4 which are adapted to connect these outermost ribbon heaters to the corresponding ribbon heaters of adjacent heater assemblies (see FIG. 4) or a common electric power supply (not shown). The one major surface or the upper surface of each of the ribbon heaters 2 (as seen in FIG. 1) has an adiabatic fabric 5 mounted thereon and the fabric is adapted to effectively direct the heat from the heater toward a surface of a structure to be heated. The adiabatic fabric 5 is preferably formed of the material sold under the trade name "KAO-WOOL". A plurality of parallel and spaced heater holder members 6 which are preferably formed of the heat-resisting and thermally and electrically insulating material sold under the trade name "Hemmit Rod" extend transversely of the juxtaposed ribbon heaters 2 at spaced points in the longitudinal direction of each of the heaters and pressed against the fabrics 5 under pressure sufficient to compress the fabrics 5 down. The holder members 6 are secured to the heaters 2 by wires

holder members 6 are secured to the heaters 2 by wires 7 in the manner which will be described hereinbelow. That is, each of the wires 7 associated with the outermost holder members 6 extends along the inner side of the associated holder member and then through transverse through holes 6a in the holder member to project out of the outer side of the holder member and the exposed opposite ends of the wire 7 are bent toward each other and bound or secured together on the outer side of the associated upright piece 2a thereby to secure the heaters to the holder members. Each of the wires 7 associated with the remaining holder members or those other than the outermost holder members extends

along the underside of the associated heater 2 and then through vertical holes 6b in the associated holder member to project out of the upper side of the holder member and the exposed opposite ends of the wire 7 are bent toward each other and bound or secured together on the upper side of the holder member thereby to apply a downward pressure to the associated heater 2 so as to hold the heater and fabric thereon together. If desired or necessary, in order to assure positive compression of the fabrics 5, in addition to the above wires 7 employed in association with the outermost holder members 6 referred to hereinabove additional wires 7 may be employed in association with the outermost holder members 6 in the same manner as mentioned in connection with the wires associated with the rest of the holder members referred to hereinabove. It will be understood that since the holder members 6 are disposed at longitudinally spaced points of each heater 2 and hold the same together, the heaters are assembled in such a manner that they are allowed to flex in the longitudinal direction. The opposite ends of each of the holder members 6 are shown as extending beyond the outer edges of the outermost heaters 2.

In order to keep the ribbon heaters 2 spaced in a predetermined relationship from a curved surface of a structure to be heated, depending legs 8 are connected to the opposite ends of each of the holder members 6 in a conventional manner and the legs depend vertically and downwardly from the upper surface of the respectively associated holder members and extend beyond the undersurfaces of the heaters 2. The legs 8 may be formed of a metal such as aluminum or any other suitable heat-resisting and insulating material.

Turning now to FIG. 4, there is shown an arrangement comprising a plurality of ribbon heater assemblies juxtaposed and electrically connected each corresponding to that shown in FIG. 1 and the arrangement is suitable employed for heating a structure having a relatively large size. However, it will be easily appreciated that if the structure is of a relatively small size, only one heater assembly is sufficient to heat such a structure. In FIG. 4, the structure to be heated is shown by reference numeral 9 and the heater assemblies 1 are disposed along the curved outer periphery of the structure with the axes of the ribbon heaters 2 in adjacent assemblies in alignment with each other and held in position by any suitable conventional means. As described hereinabove, with each heater assembly, since the holder members 6 are spaced in the longitudinal direction of the respectively associated ribbon heaters 2, the heaters and accordingly, the entire heater assembly is allowed to flex in the longitudinal direction of its heaters 2. Therefore, the heater assemblies can easily follow the curved contour surface of the structure. As shown in FIG. 5, adjacent heater assemblies are conveniently connected to each other by means of connection means 10. The connection means 10 is shown as comprising an arm 11 extending between the legs 8 of the outermost holder members 6 in the adjacent heater assemblies and screws 12 which secure the arm 10 to the adjacent legs 8. For the purpose, as shown in FIG. 1, the legs 8 associated with the outermost holder members 6 are preferably provided with threaded holes for receiving the screws 12. The conductor wires 4 of adjacent heater assemblies 1 are electrically connected to each other in any conventional suitable manner as shown at 13. The conductor wires

4 associated with the outermost holder members 6 of the outermost heater assemblies 1 in the arrangement as shown in FIG. 4 are connected to a power supply (not shown) to supply electric power to the heaters. Alternatively, the heater assemblies can be in parallel connected to the power supply. Otherwise, the heater assemblies may be conveniently connected to a three phase power supply in a conventional manner. If an arrangement comprises a great number of heat assemblies, the assemblies may be grouped into a plurality of groups and the assemblies in each group may be in series connected to each other and the groups may be in parallel connected to each other. When electric power is allowed to flow through the heater assemblies in such a multi-arrangement, the heater assemblies can radiantly heat a curved surface of a structure to perform a desired treatment on the structure.

In order to prevent the holder members from displacing due to vibrative force which will develop when electric power is supplied to the heater assembly or assemblies, the adjacent holder members can be additionally maintained in a desired or predetermined spaced relationship by means of metal wires or the like.

While there has been described what is at present considered to be the preferred embodiment of this invention, it will be obvious to those skilled in the art that various changes and modifications may be made therein without departing from the invention, and it is aimed, therefore, in the appended claims to cover all such changes and modifications as fall within the true spirit and scope of the invention. What is claimed is:

1. A heater assembly for radiantly heating a structure having a curved surface, which comprises a plurality of longitudinally flexible ribbon heaters juxtaposed in parallel and spaced relationship; means for electrically connecting said ribbon heaters comprising an upright piece extending upwardly at right angles to the plane of the heater and a conductor wire connecting said upright pieces at the corresponding one end of adjacent heaters; an electric power supply for supplying electric power to said heaters; a plurality of heat-proofing and insulating holder members extending transversely of said heaters at spaced points in the longitudinal direction of each of the heaters, each of said holder members being secured to one major surface of each of the heaters; said major surface of each of the ribbon heaters having an adiabatic fabric mounted thereon and said holder members holding the heaters and their fabrics together so as to compress the fabrics down; the outermost ones of said holder members being secured to said upright pieces of the heaters; and legs secured to said holder members at the opposite ends of each of the holder members depending vertically therefrom and extending beyond the other major surface of each of the heaters so as to hold the heaters in spaced relationship from the surface of said structure.

2. An apparatus for radiantly heating a structure member having a curved surface which comprises a plurality of heater assemblies juxtaposed, and each heater assembly comprises a plurality of longitudinally flexible ribbon heaters juxtaposed in parallel and spaced relationship; means for electrically connecting said heaters comprising an upright piece formed by upwardly bending each of the heaters at the opposite ends of the associated heater at right angles to the plane of the heater and a conductor wire connecting said upright pieces at the corresponding one end of adjacent

heaters; a plurality of heat-proofing and insulating holder members extending transversely of said heaters at spaced points in the longitudinal direction of each of the heaters, each of said holder members being secured to one major surface of each of the heaters and the outermost ones of said holder members being secured to said upright pieces of the heaters; and legs secured to said holder members at the opposite ends of each of the holder members depending vertically therefrom and

extending beyond the other major surface of each of the heaters so as to hold the heaters in spaced relationship from the surface of said structure; means for mechanically connecting the legs associated with the outermost holder members of adjacent heater assemblies and said ribbon heaters of each assembly being electrically connected to an electric power supply for supplying electric power to the heaters.
